CLAIM

The ornamental design for a thermo dispersion housing for an LED lamp, as shown and described.

(21) Appl. No.: **29/358,720**

DESCRIPTION

(22) Filed: **Mar. 31, 2010**

FIG. 1 is a perspective view of a thermo dispersion housing for an LED lamp showing this new design;

(51) LOC (9) Cl. **26-04**

FIG. 2 is a front view of a thermo dispersion housing for an LED lamp according to this specification;

(52) U.S. Cl. **D26/2**

FIG. 3 is a rear view of a thermo dispersion housing for an LED lamp according to this specification;

(58) Field of Classification Search D26/1-4;

313/313, 315, 316, 317, 318, 493; 315/52;

315/53, 56, 57, 58

FIG. 4 is a left enlarged view of a thermo dispersion housing for an LED lamp according to this specification;

See application file for complete search history.

FIG. 5 is a right enlarged view of a thermo dispersion housing for an LED lamp according to this specification;

(56) **References Cited**

FIG. 6 is a top plane view of a thermo dispersion housing for an LED lamp according to this specification;

U.S. PATENT DOCUMENTS

FIG. 7 is a bottom plane view of a thermo dispersion housing for an LED lamp according to this specification; and,

D446,321 S * 8/2001 Lin D26/24

FIG. 8 is another perspective view of the thermo dispersion housing for an LED lamp according to this specification.
